[57] **CLAIM**

The ornamental design for a tool handle, as shown and described.

DESCRIPTION

FIG. 1 is a perspective view of a tool handle showing our new design;

FIG. 2 is a top plan view thereof;

FIG. 3 is a side elevational view taken from the right of FIG. 1;

FIG. 4 is a side elevational view taken from the left of FIG. 1;

FIG. 5 is a bottom plan view;

FIG. 6 is an end elevational view taken from the top of FIG. 1; and,

FIG. 7 is an elevational view, opposite that shown in FIG. 6. The broken line showing of the blade and handle tip is for illustrative purposes only and forms no part of the claimed design.
